UNITED STATES PATENT OFFICE.

HERBERT L. STILLMAN, OF ALLENTON, RHODE ISLAND.

RAILWAY.

SPECIFICATION forming part of Letters Patent No. 341,699, dated May 11, 1886.

Application filed September 17, 1885. Serial No. 177,388. (No model.)

To all whom it may concern:

Be it known that I, HERBERT L. STILLMAN, a citizen of the United States, residing at Allenton, in the county of Washington and State of Rhode Island, have invented certain new and useful Improvements in Railways; and I do hereby declare the following to be a full, clear, and exact description of the invention, such as will enable others skilled in the art to make and use the same.

The invention relates to improvements in railways, and is more particularly adapted for use in short ways on which light engines are used; and it consists in the construction, novel arrangement, and adaptation of devices, as will be hereinafter more fully set forth and claimed.

In the annexed drawing the figure is a representation of a railway constructed according to my invention.

Referring by letter to the said drawing, A indicates the stringers, which are arranged parallel, and are provided on their upper sides at suitable intervals with transverse recesses *a*, to receive the opposite ends of the ties B, which latter are placed in the said recesses so as to lie flush with the upper sides of the stringers and receive the rails C.

D indicates posts which engage the stringers at suitable points along their length to support the same, and these posts have a bearing in broad feet composed of blocks E, the said posts being firmly spiked or otherwise secured to the blocks. These posts are designed to be placed a sufficient distance in the ground, resting on the said blocks, except at cuts, draws, hollows, &c., where they may be partly exposed. By this construction it will be seen that a broad and firm bearing is given to the track, and tilting and lateral motion and upheaving of the track is prevented.

Having described this invention, what I claim is—

The improved railway herein described, consisting of the parallel stringers having their upper sides recessed at *a*, the cross-ties arranged in the said recesses, the posts engaging the under sides of the said stringers, the blocks arranged beneath the posts in the ground, and the track-rails secured to the stringers and cross-ties, substantially as specified.

HERBERT L. STILLMAN.
